Primary Examiner—Charles A Rademaker(74) *Attorney, Agent, or Firm*—Tillman Wright, PLLC; Chad D. Tillman; James D. Wright(57) **CLAIM**

The ornamental design for a food container assembly, as shown and described.

DESCRIPTION

FIG. 1 is a perspective view of a food container assembly in accordance with an embodiment of the present invention; and,

FIG. 2 is a side elevational view of the food container assembly of FIG. 1, which view is identical from each of the four sides of the food container assembly.
